SERVICE OFFICE BUILDING FOR FILLING STATION ISLANDS

Charles E. Knox, Jr., 1007 Slocum St., Dallas, Tex.

Filed Mar. 2, 1959, Ser. No. 54,787

Term of patent 14 years

(Cl. D13—1)

FIGURE 1 is a side elevational view of a service office building for filling station islands, showing my new design;

FIGURE 2 is a rear elevation of my design;

FIGURE 3 is a side elevation opposite that of FIGURE 1 of my design;

FIGURE 4 is the front end elevation of my design, and

FIGURE 5 is an enlarged fragmentary vertical sectional view taken on line 5—5 of FIGURE 1.

The design is characterized by the portions of the drawings shown in full line.

I claim:

The ornamental design for a service office building for filling station islands, substantially as shown and described.
